UNITED STATES PATENT OFFICE.

DONALD G. MCLEAN, OF BOSTON, MASSACHUSETTS, ASSIGNOR TO THE RANDALL-FAICHNEY COMPANY, OF BOSTON, MASSACHUSETTS, A CORPORATION OF MASSACHUSETTS.

SIGNALING DEVICE.

1,113,673.

Specification of Letters Patent.

Patented Oct. 13, 1914.

Application filed July 2, 1912. Serial No. 707,213.

To all whom it may concern:

Be it known that I, DONALD G. MCLEAN, a citizen of the United States, residing at Boston, in the county of Suffolk and State 5 of Massachusetts, have invented a new and useful Improvement in Signaling Devices, of which the following is a specification, reference being had therein to the accompanying drawings.

10 This invention relates to signaling devices and more particularly to that class of signaling devices which are sounded by the exhaust gas from an engine.

15 The object of the invention is to provide means by which the signaling device may be rendered operative from a distant point without impeding the free use for other purposes of the hands or feet of the operator.

20 In accordance with this object one feature of the invention contemplates the provision of electrical connections between the device and the point of operation thereof, which connections preferably comprise a push button near the operator and a motor having 25 its movable member connected with the movable part of the device which is operated to cause the exhaust gas to sound an alarm.

30 Another feature of the invention comprises means in a signaling device of the character described for automatically reducing the current supplied to the motor after the moving part of the device has 35 been thrown into operative position.

In the best form at present known to the inventor, the motor consists of a solenoid having an armature connected with the movable member of the signaling device.

40 Provision is made for increasing the resistance of the coils of the solenoid after a pre-determined movement of the armature and so reducing the amount of current consumed thereby.

45 These features and such others as may hereinafter appear will best be understood from the following description and accompanying drawings, in which:—

Figure 1 is a general view of my improved signaling device applied to an auto-

mobile; Fig. 2 is a detail view of the solenoid which provides the motive power to render the signal operative; Fig. 3 is a longitudinal section through the center of the solenoid, and Fig. 4 is a diagrammatic view of the electrical connections.

The signaling device may comprise any of the well known horns which are operated by the engine exhaust, such, for instance, as that shown in the drawings, 60 where a horn 1 is attached to an exhaust pipe 2 leading from a muffler 3 into which the engine discharges the burned gas through a pipe 4. In the type of horn shown, a gate 5 is normally held open by a 65 spring 6 which allows the gas to escape from the exhaust to the atmosphere without sounding the horn, but when the gate is closed, the exhaust gas is deflected toward a lip 7 which causes an audible alarm to 70 sound. As at present constructed, this horn is thrown into operation by a cord connecting the gate 5 with a lever near the seat which is operated by the driver's hand or foot. This is objectionable as it interferes 75 with his operation of the various treadles or the steering wheel and parts carried thereon, as the case may be.

In the present invention the gate 5 is connected by a cord 8 with a rod 9 secured 80 to the armature 10 of a solenoid 11. A spring 13 may be inserted between the ends of the cord to allow the gate 5 to yield to prevent the exhaust when too violent sounding a harsh or shrill note. The solenoid is 85 inclosed in a casing 12 (Fig. 3) which may be secured beneath the body of the car in any convenient position, as is shown in Fig. 1 and one end of the casing is closed by a head 14 to which is secured a fixed core 15 90 and the other end is closed by a head 16 through which the rod 9 passes. Some form of stuffing box is desirable to prevent dust and water from entering the casing around the rod 9 and it has been found most expedient to employ the construction shown in Fig. 3 which avoids all excessive friction on the rod. A cover 17 of flexible material, such as leather, is secured at its periphery, to the head 16 by a ring 30, the 100

center of the cover being fastened to the rod 9 at some distance from the head so as to permit movement of the rod.

The solenoid 11 is energized by electricity from any convenient source of supply, as from a battery 18. A wire 19 connects the battery with one end of a coil 20 in the solenoid, the other end of the coil being connected with a spring-switch 21 and with a second coil 22, which is in effect a continuation of the coil 20 but is preferably made of wire of higher resistance than that in the first coil. To the end of the solenoid is secured the spring-switch 21 having its free end normally in contact with a screw 23 carried by a bracket 31 which is mounted on the end of the solenoid. The end of the switch 21 projects somewhat beyond the screw 23 so as to be engaged by an insulated collar 24 which is secured to the armature 10. The other pole of the battery 18 is connected by a wire 25 with a push button 26 and a wire 27 leads from the push button to the end of the coil 22 and also to the screw 23. The push button may be in any convenient position for the driver but is preferably mounted in the rim of the steering wheel so that he can operate the horn without removing his hands from the wheel or his feet from the treadles. The push button and its connections with the horn may, if desired, be used as an auxiliary to the usual lever control.

Referring now more particularly to Fig. 4, it will be seen that when the button 26 is first pushed to close the circuit, the current, assuming it to flow with the arrow through the wire 19, will then pass through the solenoid to the coil 20 and through the switch 21 and screw 23 to the wire 27 and back to the battery. The current will take this course rather than through the coil 22 as it offers much less resistance. When the armature has moved a certain distance, which may be adjusted by means of the screw 23, the collar 24 breaks the contact between the switch 21 and the screw 23. The current must then return through the coil 22, but on account of the higher resistance of this coil there will be a very small flow of current. The strength of the solenoid is proportionate to the ampere turns and it is apparent that a strong pull will be exerted upon the armature 10 when the circuit is first closed and the current is flowing through the coil 20 only. The pull exerted upon the armature will increase as the armature moves into the solenoid until the movement of the switch 21 breaks the circuit. This strong pull will overcome the tension of the spring 6 and through the medium of the cord 8 will close the gate 5 thereby sounding the alarm. When the gate is in a closed position less current is necessary to maintain it in that

position than is required for the operation 65 of closing it and therefore the screw 23 should be so adjusted that the circuit through the switch 21 will be broken just before the armature reaches the end of its movement and the horn will continue to be 70 sounded at a relatively small expense of current flowing through both the coils 20 and 22. In order to secure a stronger pull at the beginning of the inward movement of the armature and therefore a more even pull 75 throughout its movement, the end of the core 15 is made like the frustum of a cone and the adjacent end of the armature 10 is bored out to a corresponding shape. This will result in a more positive action of the armature 80 when the circuit is closed by operating the push button.

This invention has been described in connection with a gas engine and a horn which is rendered operative by the movement of a 85 gate. It will be apparent to one skilled in the art to which this invention relates that the exhaust from engines using other motive power than gas may be employed and that other forms of horns, in which other parts 90 or the horn itself are moved, may be substituted for that shown and described. Other changes may also be made in the form, character, and relation of the parts without departing from the scope of the invention as 95 defined in the appended claims.

What I claim is:

1. A signaling device comprising a horn, mounted on the exhaust pipe of an internal combustion engine, and having a movable part to operate it, in combination with a solenoid having a core connected with the movable part of the horn, an open-circuit battery for energizing the solenoid having two windings of unequal resistance, and a 100 cut-out short circuiting one of the windings upon the closing of the energizing circuit and operating to throw the windings into series when said core has moved to a certain point, so as to decrease the amount of current passing from the battery automatically. 105

2. A signaling device comprising a horn mounted on the exhaust pipe of an internal combustion engine, a solenoidal operating device for controlling said horn, a battery 115 for energizing the solenoid, a normally open circuit connecting the solenoid and battery, said solenoid having provision for operating on the closing of the circuit to draw a large amount of current supply from the battery 120 and thereafter automatically to increase the resistance so as to reduce the amount of current passing from said battery.

3. A signaling device comprising a horn mounted in the exhaust pipe of an engine, 125 and having a movable part to operate it, in combination with a solenoid of two unequal windings having a core connected with said

movable part, a battery for energizing said solenoid and a spring situated between said core and said movable part controlling and equalizing the amount of sound passing from said horn.

5 In testimony whereof, I hereunto set my hand in the presence of two subscribing wit-

nesses, this the twenty-eighth day of June, 1912.

DONALD G. McLEAN.
